UNITED STATES PATENT OFFICE.

CHRISTOPHER R. RYAN, OF CUBA, NEW YORK.

SCREEN.

Application filed October 3, 1925. Serial No. 60,274.

To all whom it may concern:

Be it known that I, CHRISTOPHER R. RYAN, a citizen of the United States, and a resident of Cuba, in the county of Allegany and State 5 of New York, have invented a new and Improved Screen, of which the following is a full, clear, and exact description.

This invention relates to screens and more particularly to window screens of the adjustable type which may be extended so as to fit any ordinary window frame and held in position between the beads of the window frame by the window sash resting on the screen.

15 An object of the invention is to provide a screen of this character in which two movable frames are provided slidably connected by bendable coupling devices which enable the frames to be disconnected to allow new netting or screening to be inserted in the frames or for any other reason desired.

20 A further object is to provide a screen of this character having a curtain or shade which is movable across the screen and guided by elastic tapes so that the curtain or shade may entirely cover the netting of the screen or partially cover the same, as may be desired.

25 A further object is to provide a device of this character which functions not only as a screen but also as a ventilator, which enables the window to be left open even in stormy weather.

30 A further object is to provide a screen of this character which will be neat and attractive in appearance and which will be strong and durable in use.

35 With these and other objects in view, the invention consists in certain novel features 40 of construction and combinations and arrangements of parts, which will be more fully hereinafter described and pointed out in the claims.

In the accompanying drawings—

45 Figure 1 is a view in front elevation of my improved screen;

Figure 2 is an enlarged view in vertical section on the line 2—2 of Figure 1;

50 Figure 3 is an enlarged fragmentary view in longitudinal section on the line 3—3 of Figure 1;

Figure 4 is an enlarged fragmentary view in longitudinal section on the line 4—4 of Figure 1.

55 My improved screen comprises two frames 1 and 2, both of which may be of wood or

any other suitable material. Each frame is of general rectangular form and both of the same height or vertical dimension.

Each frame 1 and 2 is provided with a recess 3 in which a wire or other netting 4 is secured by a covering strip 5 flush with the face of the frame. Each frame is formed at one end with a strip 6 which projects inwardly toward the netting of the other frame so as to prevent flies, mosquitos and other insects from passing between the frames.

Both frames 1 and 2 are provided in their horizontal upper and lower bars with longitudinal slits 7, and bendable metal strips 8 are secured to each frame and projected through the slits 7. The strips 8 of each frame are projected through the slits 7 of the other frame and then bent downwardly 75 against the frame, forming holding tongues 9 which hold the frames together and allow them a sliding movement relative to each other but they can be bent at right angles to allow the frames to be separated when it is 80 desired to insert new netting into the frames. These slits 7 are very narrow and also the metal strips 8 are correspondingly narrow so that there is not sufficient space or opening for mosquitos or the like to pass through 85 the slits.

Each frame 1 and 2 is preferably strengthened at the corners by angle brackets 10, and elastic tapes 11 are located at the upper and lower portions of the screen, and secured at 90 one end to frame 1 and at their other ends to frame 2, so that these tapes being of elastic material allow the frames to be moved relatively to each other and at all times remain taut.

95 Figure 12 represents a curtain or shade. This curtain is mounted on a spring roller 13 supported in suitable brackets 14' on frame 1 adjacent the end of the latter. The shade 12 is provided with guide loops 14 receiving the strips 11 so that the shade can be drawn off the roller or allowed to wind thereon and be guided in its movement always by the strips 11. The shade is also provided with a hook 15 to engage in an eye or hook 16 on frame 2 to hold the shade fully extended covering the netting of the screen.

100 It will thus be noted that if the well known type of ratchet spring roll is provided, the shade can be drawn from the roll as far as 110 desired or can be completely extended at the will of the operator.

Various slight changes and alterations might be made in the general form of the parts described without departing from the invention and hence I do not limit myself to the precise details set forth but consider myself at liberty to make such slight changes and alterations as fairly fall within the spirit and scope of the appended claims.

I claim:

- 10 1. A screen of the character described, comprising two screen members movable relatively to each other, elastic tapes connecting the respective members and located adjacent the upper and lower edges of the screen, a spring roller adjacent one end of one mem-

ber, a curtain wound on said roller, and guides on the shade movable on the tapes.

2. A screen of the character described, comprising two screen members movable relatively to each other, elastic tapes connecting the respective members and located adjacent the upper and lower edges of the screen, a spring roller adjacent one end of one member, a curtain wound on said roller, guides on the shade movable on the tapes, a hook on the free end of the shade, and a member on the screen frame adapted to hold the shade fully extended.

CHRISTOPHER R. RYAN.
